UNITED STATES PATENT OFFICE.

EDWARD SANFORD CHARLES, OF CHICAGO, ILLINOIS, ASSIGNOR, BY MESNE ASSIGNMENTS, TO INTERNATIONAL HARVESTER COMPANY, A CORPORATION OF NEW JERSEY.

FEEDING MECHANISM FOR ENSILAGE-CUTTERS.

1,316,081.

Specification of Letters Patent. Patented Sept. 16, 1919.

Application filed February 19, 1916. Serial No. 79,273.

To all whom it may concern:

Be it known that I, EDWARD S. CHARLES, a citizen of the United States, residing at Chicago, in the county of Cook and State of Illinois, have invented certain new and useful Improvements in Feeding Mechanism for Ensilage-Cutters, of which the following is a full, clear, and exact specification.

My invention relates to feeding mechanism for ensilage cutters.

It has for its object to limit the amount of material fed to the feeding rolls of an ensilage cutter in such a manner as to reduce the amount of separation thereof by 15 the ensilage to a certain limit well within the capacity of the driving mechanism for rolls and thereby eliminate the breaking of these connections and consequent expense and delay in the operation of the machine. 20 I attain this object by providing improved means whereby the amount of material which may be fed between the rolls is held within a predetermined limit, all as herein-after more fully described.

25 In the accompanying drawings, I have, for purposes of illustration, shown one embodiment which my invention may assume in practice.

In these drawings:

30 Figure 1 is a side view, partially in longitudinal section, of an ensilage cutter equipped with my improvement;

Fig. 2 is a detail transverse sectional view of the mechanism shown in Fig. 1, taken 35 substantially on the line 2-2 and looking in the direction of the arrows; and Fig. 3 is a detail view illustrating the connection between the floating feed roll and the movable feed roll.

40 The ensilage cutter shown is of standard construction, including a frame 1 mounted upon wheels 2 and carrying a suitable cutter head 3 inclosed in the usual casing 4 and receiving ensilage from rotatable feeding rolls 5, 6, respectively, disposed one above the other. These rolls receive ensilage from a longitudinally movable conveyer 7, a floating feed roll 8 being disposed above the delivery end of the conveyer and pivotally 45 connected to the movable upper feed roll 6 by means of a link connection 9 and driven therefrom by means of a driving connection 10. As in the standard construction, the upper feed roll 6 is movable vertically in 50 slots 11 formed in standards 12 disposed on

opposite sides of the frame and between the casing 4 and floating feed roll 8. The lower feed roll 5 rotates about a fixed axis.

In my improved construction a stalk stopping member or plate 13 is extended 60 transversely between the front upper edges of standards 12 and attached thereto by any suitable means, as, for instance, bolts 14, the upper end of the plate preferably being turned substantially at right angles in such 65 a manner as to rest upon the tops of the standards 12. As shown, this member 13 extends downward and vertically to a point slightly above the bottom of the roll 6, when the latter is raised to its desired upper limit 70 of movement in the slots 11 and is located between the standards 12 and the floating feed roll 8.

In the operation of my improved construction, it is obvious that as the ensilage is 75 fed forward by the conveyer 7, the floating feed roll 8 will operate thereon to compress the charge, and this floating feeder 8 will be free to move upward through its link connection 9, the ensilage passing between the 80 rolls 5 and 6. As the bulk of the charge increases, the roll 6 will be moved upward to the position shown in dotted lines in Fig. 1, the throat then being open at its maximum. In this position it will be noted that the 85 plate 13 is disposed in the path of butts of the stalks fed to the roll 6 and that this plate acts to prevent the entry of more stalks between the rolls 5 and 6, the butt ends of the stalks being held by the plate against 90 further inward movement by the floating feeder 8 until the lower stalks have been fed through the rolls 5 and 6 to the cutter head, whereupon the feeder 8 will depress the surplus stalks and feed them through in 95 the usual manner between the rolls 5 and 6.

In operation it has been found that by the provision of my improved plate 13 the movement of the roll 6 is held within such limits as to prevent any breakage of its usual 100 driving connections and that an exceedingly even and constant feed is produced, the plate 13 preventing the choking of the rolls when a too great amount of ensilage is fed to the same, and the breakage of the driving 105 connections and thereby enabling the machine to be operated continuously with less expense.

While I have in this application specifically described one embodiment which my 110

invention may assume in practice, it is, of course, to be understood that the form thereof shown herein is used for purposes of illustration and that the invention may be modified to assume other forms without departing from its spirit, it being my intention to include all such modifications within the scope of the appended claim.

What I claim as new is:

- 10 In an ensilage cutter, a frame, a pair of feed rolls carried thereby and disposed one above the other, the upper feed roll being vertically movable, conveyer mechanism

delivering material to said feed rolls, a floating feed roll pivotally connected to said vertically movable feed roll and disposed over the delivery end of said conveyer mechanism, and a vertically disposed plate rigidly mounted on said frame between said floating feed roll and said movable feed roll, said floating feed roll having its lower engaging surface normally disposed below the upper surface of said vertically movable feed roll and below the lower edge of said plate.

In testimony whereof I affix my signature. 25
EDWARD SANFORD CHARLES.
